EDMUND M. GOODEBODY, OF BROOKLYN, NEW YORK, ASSIGNOR TO INTEERTYPE CORPORATION, OF BROOKLYN, NEW YORK, A CORPORATION OF NEW YORK.

TYPOGRAPHICAL MACHINE.

Application filed June 21, 1922. Serial No. 569,778.

To all whom it may concern:

Be it known that I, EDMUND M. GOODBODY, a citizen of the United States, residing at Brooklyn, in the county of Kings and State 5 of New York, have invented new and useful Improvements in Typographical Machines, of which the following is a specification.

The present invention relates to improvements in typographical machines and more especially to those of the class shown and described generally in U. S. Letters Patents Nos. 436,532 granted September 16, 1890, and 557,000 granted March 24, 1896, wherein 10 a font of matrices which are stored in a magazine are released by actuation of the respective keys of a keyboard and descend by gravity through appropriate delivery channels onto a constantly running downwardly 15 inclined delivery belt which passes beneath the different delivery channels, the belt operating to deliver the matrices to an intermediate assembling mechanism, which latter delivers the matrices to the assembling point 20 at the entrance to assembling means, usually a so-called assembling elevator, where the matrices are assembled into a line preparatory to the casting of a type bar or slug therefrom.

25 In machines of this class as commercially built, the matrices are assembled to form a line with the matrices therein standing in upright or vertical position, whereas the delivery belt is inclined downwardly toward 30 the point at which the line is assembled, in consequence of which the matrices must be diverted from the downwardly inclined path which they follow while lying flatwise on 35 the delivery belt, to the upright position for assembly, and this diversion of the matrices 40 takes place while the latter are passing from the delivery belt to the assembling point, a continuously revolving toothed member of so-called star wheel being located 45 opposite to the entrance to the assembling elevator and functioning to stack the matrices successively into the line. The space between the matrix discharge end of the delivery belt and the star wheel is usually 50 termed the neutral zone or field and it is at this point that the matrices must be diverted from the inclined path imparted to them by the belt, to the vertical or upright position required for assembly of the matrices into 55 the line. Heretofore the matrices have been

required to traverse this neutral zone by their own momentum and while they are being diverted from the inclined to the upright or vertical position, and in consequence, owing to rapid operation of the keyboard or 60 other causes, disturbances frequently occur at this neutral zone which result in transposing of matrices in the line, jamming or clogging of the matrices at the star wheel or 65 the entrance to the assembling elevator, or other faulty operation occurs which interferes with the regularity of composition and causes delay in the operation and errors in 70 the product of the machine.

The object of the present invention is to 75 overcome these defects which have been found to exist in machines of this class as heretofore constructed, thus insuring regularity in composition and avoiding delays in 80 operation and errors in the product of the machine. According to the present invention, the so-called neutral zone between the matrix delivery belt and the star wheel is eliminated or dispensed with, there being no appreciable gap between the delivery end of 85 the belt and the star wheel, and a tensioned chute plate is located opposite to the matrix-engaging surface of the travelling belt, the chute plate embodying a toe which is immediately below or beyond the point where the 90 delivery belt first bends downwardly over its lower pulley, this toe of the chute plate being thus positioned to engage the foot or leading edge of each matrix as it reaches the toe and to thus deflect the matrix from its inclined position to or toward an upright position, so that the matrix will be conducted directly and with certainty into a position 95 in front of the star wheel, thus insuring its proper assembly into the line. The tension of the chute plate operating in conjunction 100 with the continuously travelling matrix-engaging surface of the belt which passes opposite to the toe, insures the delivery of the matrices successively and in proper order 105 from the delivery belt, notwithstanding that two or more matrices delivered in rapid succession from adjacent delivery channels of the magazine may be deposited in overlapping relation onto the belt, as the portion of the travelling belt opposite to the toe of the chute plate will draw the foremost matrix 110 yieldingly pressed against the travelling surface of the belt by the chute plate forward, thereby disengaging it from the

matrix which it overlaps and insuring its delivery to the star wheel in advance of the following matrix. These operations take place without jamming or clogging of the 5 matrices either at the chute plate or at the entrance to the assembling elevator.

To this end, the invention consists in certain improvements and combinations and arrangements of parts, all as will be hereinafter more fully described, the features of 10 novelty being pointed out particularly in the claims at the end of the specification.

In the accompanying drawing:—

Figure 1 is a front elevation of the assembling mechanism of a typographical machine constructed in accordance with the present invention, and

Figure 2 is a perspective view showing the driving means for the working parts 20 of the assembling mechanism.

The present invention is particularly applicable to typographical machines of the class shown and described generally in the patents above referred to, the invention 25 being shown applied to a machine of that class in the present instance, wherein 1 represents the assembling elevator which may be of the usual construction having a channel open at its right-hand end in Figure 1 to successively receive matrices M and to support these matrices to form a line, a line being shown in course of assembly in Figure 1. The matrices which are stored 30 in the respective channels of a magazine 35 are released for delivery by actuation of the respective keys of a keyboard, the construction and operation of which is well understood in the art, the released matrices descending by gravity through channels formed 40 between guides 2. The matrices thus delivered from the magazine are deposited onto a continuously travelling belt 3 which extends past the lower or matrix delivery ends of the guides 2 and is inclined downwardly toward the assembling elevator. The 45 matrices when received by the belt lie in a flatwise position thereon, as is shown in Figures 1 and 2, the foot or lower end of the matrix being foremost. The belt, which is endless, passes at its upper end over an 50 idler pulley which is not shown, but which may be of the usual construction, and the lower end of the belt passes around a driving pulley 4. According to the present invention, the pulley 4 is of smaller diameter 55 than that usually employed in machines of this class and this pulley also is located in close proximity to the entrance to the assembling elevator 1, thus bringing the 60 matrix discharging end of the belt into closer relation to the assembling elevator and also giving the belt a steeper incline than that heretofore usually employed. Between the assembling elevator 1 and the belt 65 pulley 4 is mounted a toothed member

usually termed a star wheel 5, this star wheel being revolvably mounted between the matrix entrance to the assembling elevator and the belt pulley 4, the star wheel being in close relation to these elements of the 70 assembling mechanism and being driven continuously in a direction that carries its upper portion toward the entrance to the assembling elevator. A relatively short bridge 6 is preferably provided at a point 75 beyond the point X where the belt first bends downwardly around the pulley 4, this bridge occupying a position in close proximity to the surface of the belt which is on the periphery of the pulley 4 and immediately above the star wheel, so that it bridges the slight gap between the belt and the star wheel and thus prevents catching 80 of a matrix which might be delivered in a faulty way from the belt in the crevice between the belt and the adjacent side of the star wheel.

Any suitable means may be provided for driving the belt 3 and the star wheel 5 continuously and at the appropriate speeds. 90 As shown, a pulley 7 is mounted on the pivot 8 and is driven continuously by a belt 9, which latter may be driven continuously from any constantly revolving part of the machine, as is usual. The pulley 7 operates through gears 10 and 11 to drive a gear 12, which latter is fixed to the shaft 13 of the belt-driving pulley 4, whereby the latter receives its continuous motion, and other gears 14 and 15 operate to drive a gear 16, the latter being fixed to the shaft on which the star wheel 5 is mounted, whereby the latter is driven continuously and in the same direction as the pulley 4.

The present invention provides a tensioned chute plate having a toe located opposite to the matrix-engaging surface of the belt 3 at a point below or beyond the point X, at which the belt 3 first bends downwardly around the pulley 4, the toe of the chute plate functioning to engage and deflect the matrices in course of delivery by the belt 3 from their inclined position to or toward an upright position, whereby the matrices are conducted directly toward a position in front of the star wheel, so that they will be correctly stacked in the line in course of assembly in the assembling elevator. This chute plate, by reason of the yielding pressure which it exerts, will not only accommodate itself to the passage of matrices having different body thicknesses, but will also cause separation and delivery in proper order of overlapping matrices which may reach the chute plate, the latter in such case exerting a yielding pressure upon the foremost overlapping matrix that will cause the travelling belt, which is opposite to the toe of the chute plate and which is in engagement with this matrix, to draw the same for- 105 110 115 120 125 130

wardly thereby separating it from the following matrix which it overlaps, thus avoiding jamming of the matrices and also transposing of the matrices in the line. Preferably and as shown, the chute plate, designated 17, is pivoted at 18 to a relatively fixed part of the machine and has a toe 19 at or toward its lower end, this toe being located opposite to the belt 3 at a point adjacent to or preferably slightly beyond the point X, at which the belt 3 first bends over the pulley 4. The chute plate has an extension 20 to which a tension spring 21 is attached, this spring acting to yieldingly force the toe 19 of the chute plate toward the surface of the belt 3. A pin or other stop 22 may be provided to co-operate with the extension 20 on the chute plate and thus limit the movement of the chute plate under the action of the spring 21, so that the toe 19 will not bear or ride directly on the belt 3 while no matrices are passing the chute plate.

The operation of matrix assembling mechanism constructed in accordance with the present invention, as hereinbefore described, is as follows: Assuming that the belt 3 and the star wheel 5 are being driven continuously, the matrices released from the magazine by operation of the keyboard in the usual way drop through the channels between the guides 2 onto the upper stretch of the travelling belt 3, these matrices lying flatwise on the upper surface of the belt with their feet or lower ends directed forwardly and the matrices will travel with the belt in a downwardly and forwardly inclined direction. As each matrix reaches the point X at which the upper stretch of the belt 3 first bends around the pulley 4, the matrix, owing to its inclined position and the momentum which it has gained while travelling in an inclined path with the upper stretch of the belt 3, will begin to discharge from the belt, the matrix having a tendency to continue its movement in the inclined direction while the belt bends around the pulley 4. At this moment the foot or leading edge of the matrix strikes the toe 19 of the chute plate. While the chute plate is under the tension of the spring 21, which enables the chute plate to accommodate itself to the passage of matrices having different body thicknesses, yet the tension on the chute plate is sufficient to hold the toe 19 thereof in a position below the plane of the top stretch of the belt 3 in opposition to the impulse received by it from the passing matrix, so that the foot or leading edge of this matrix will be diverted from its inclined path downwardly and as the body of this matrix passes the toe of the chute plate the matrix will be deflected into or toward an upright or vertical position. During the passage of the matrix past the toe of the

chute plate the matrix remains in contact with the surface of the belt 3, so that the latter continues to cause or control the advance of the matrix, and as the matrix continues to advance it assumes an upright or vertical position in front of the star wheel 5, and the latter then acts in the usual way on this matrix to stack it in the line in course of formation in the assembling elevator 1. The bridge 6 which is relatively short is in a position to catch the foot or leading edge of any matrix which may have a tendency to deposit behind the star wheel, the bridge in such case directing the matrix into its proper position in front of the star wheel. If two matrices should be delivered almost or practically simultaneously onto the belt from adjacent matrix delivery channels, the foremost of such matrices would be likely to overlap the following matrix. When the foremost of such overlapping matrices reach the chute plate, the foot or leading edge of the foremost matrix will first engage the toe 19 and this toe will yieldingly press this part of the leading matrix into engagement with the portion of the travelling belt opposite to the toe, in consequence of which the belt will pull the leading matrix forward and thus insure its delivery to the star wheel in advance of the delivery of the following matrix, which it overlapped, the star wheel acting to introduce the leading matrix into the line before the following matrix reaches the star wheel.

By eliminating the gap or neutral zone between the belt and the star wheel, and providing a chute plate, the operative toe of which is located below or beyond the point where the belt first bends over its lower pulley and directly opposite to a portion of the face of the travelling belt, the matrices are mechanically controlled while they are being diverted and conducted from the belt to the assembling point, thereby insuring the proper delivery of the matrices to the assembling point, and furthermore, should matrices in overlapping relation reach the chute plate, which is likely to occur when the keyboard is operated rapidly, the foremost matrix will be yieldingly pressed by the toe of the chute plate against the travelling belt and hence the foremost matrix will be drawn ahead and thereby separated from the following matrix and it will be delivered to the assembling point in advance of the following matrix which it had overlapped, in consequence of which transposing of matrices in the line is avoided and also jamming or clogging of the matrices at the chute plate or the assembling point is prevented. The relative arrangement of the lower belt pulley, star wheel and chute plate, according to the present invention, also enables the belt to be placed at a

steeper incline than has heretofore been possible, and this is advantageous as it facilitates the delivery of the matrices from the delivery channels of the magazine to the assembling point.

I claim as my invention:—

1. In a typographical machine of the class wherein matrices are delivered from a magazine and assembled in a line, the combination of assembling means in which the matrices are assembled in a line, a revoluble toothed member for stacking the matrices in a line, a matrix delivery belt inclined downwardly toward the assembling point and arranged to receive the matrices delivered from the magazine, a pulley over which said belt passes, said pulley being located immediately adjacent to said toothed member, and a chute plate having a toe located opposite to the portion of the travelling belt beyond the point at which the belt first bends over said pulley and operative to divert the leading ends of the matrices from the inclined position which they occupied while travelling with the belt toward an upright position and tensioned to press the matrices while passing the toe into contact with the travelling surface of the belt opposite to the toe.

2. In a typographical machine of the class wherein matrices are delivered from a magazine and assembled in flatwise relation in a line by a star wheel, the combination of an inclined travelling belt arranged to receive the matrices delivered from the magazine, a driving pulley over which the belt passes, said pulley being located contiguous to the star wheel, and a tensioned diverting plate located below the point at which said belt first bends over said pulley and opposite to the travelling surface of the belt, said plate being operative to divert the matrices as they are delivered from their inclined position on the belt to a substantially vertical position in front of the star wheel, the pressure exerted by the diverting plate on the matrices while passing between the diverting plate and the opposed surface of the travelling belt insuring rapid delivery of the matrices to the star wheel.

In testimony whereof I have hereunto set my hand in presence of two subscribing witnesses.
